(57) **CLAIM**

We claim the ornamental design for a packaging for food product, as shown and described.

DESCRIPTION

FIG. 1 is a perspective view of a first embodiment of packaging for food product, showing our new design;
FIG. 2 is a bottom view thereof;

FIG. 3 is a top view thereof;

FIG. 4 is a right side view thereof;

FIG. 5 is a left side view thereof;

FIG. 6 is a front side view thereof;

FIG. 7 is a rear side view thereof;

FIG. 8 is a top perspective view of a second embodiment of packaging for food product;

FIG. 9 is a bottom view thereof;

FIG. 10 is a top view thereof;

FIG. 11 is a right side view thereof;

FIG. 12 is a left side view thereof;

FIG. 13 is a front side view thereof; and,

FIG. 14 is a rear side view thereof.

The dash-dot boundary line(s) defines the boundary of the claimed design and forms no part of the claimed design. The broken lines in the drawings form no part of the claimed design and are only for illustrative purposes, and/or to show environmental structure.
